UNITED STATES PATENT OFFICE.

CHARLES A. BRAY AND FLORIEN C. FRY, OF SCHENECTADY, NEW YORK,
ASSIGNORS TO GENERAL ELECTRIC COMPANY, A CORPORATION OF NEW
YORK.

TROLLEY-POLE.

SPECIFICATION forming part of Letters Patent No. 725,667, dated April 21, 1903.

Application filed September 17, 1902. Serial No. 123,671. (No model.)

To all whom it may concern:

Be it known that we, CHARLES A. BRAY and FLORIEN C. FRY, citizens of the United States, and residents of Schenectady, county 5 of Schenectady, State of New York, have invented certain new and useful Improvements in Trolley-Poles, of which the following is a specification.

Our invention relates to improvements in 10 trolley-poles in use on vehicles traveling in contracted passages, such as mine-passages. The main tunnels of the mine are frequently very narrow, but of considerable depth, while other passages of the mine may be shallow 15 and broad. This is especially true of coal-mines, where the coal-chambers are of a depth equal to the thickness of the coal-seam, which may be quite small, the chambers, however, being quite wide.

20 The object of our invention is the construction of a trolley-pole which will adjust itself to contact either with a conductor above the vehicle carrying the trolley or one at the side of the vehicle and at a level with or below the top of the vehicle.

Our invention consists in certain features, which will be more fully pointed out in the claims.

In the drawings, Figure 1 is a side view of 30 a mining-locomotive provided with a trolley-pole embodying our invention. Fig. 2 is a partial end view of the same construction.

A mining-locomotive 1 is conventionally shown as resting on the rails 2, a trolley-pole 35 3 being revolvably mounted on the locomotive at the rear end in the usual manner. The trolley-pole is made in sections, of which the first section 4, preferably made out of wood, is clamped in a socket 5, which is pivoted to 40 the trolley-base 6. The other section 7, which is preferably made of metal tubing, has a straight portion 8, which receives the end of the lower section 4. Another portion 9 of this section, which is substantially parallel 45 to the portion 8 and to section 4, is connected to the portion 8 by an intervening angular portion 10. At the outer end of the section 7 the trolley-wheel holder 11 is

clamped. The trolley-wheel 12 is mounted in the holder in the usual manner and engages with the conductor 13.

The trolley-pole when in the position indicated by the dotted lines in Figs. 1 and 2 is adapted to engage the conductor above the locomotive in the ordinary manner; but 55 when in the position shown in full lines it may engage the conductor carried at one side of the vehicle and at a level with or lower than the top of the vehicle. A trolley-pole thus constructed will, by its engagement with 60 the conductor, automatically shift its position from that shown in the dotted-line construction to that shown in the full-line construction, and of course will follow a conductor in any intermediate position. 65

By properly proportioning the parts the pole can be used to contact with a wire which is at a level considerably lower than that of the top of the car. The vertical displacement of the trolley-wheel 12 with respect to 70 the pole-section 4 may be varied somewhat, if desired, by rotating the pole with respect to the socket-pieces 11 and 5. In place of the simple trolley-wheel holder 11 shown a trolley-wheel holder provided with a swivel 75 joint may be used, so that the plane of the trolley-wheel will always be parallel to the conductor. In practice, however, we have found that the slight angular displacement 80 of the trolley-wheel with respect to the conductor is unimportant.

While we have illustrated and described the best form of our invention which is now known, we do not desire to be limited to the exact details of construction shown.

What we claim as new, and desire to secure by Letters Patent of the United States, is—

1. In combination, a conductor, a vehicle, and a trolley-pole revolvably mounted on top thereof, the said pole having a bent portion 90 intermediate its ends, whereby the trolley-pole may adjust itself to contact with the conductor when above the level of the top of the vehicle or when at the side of and not higher than the top of the vehicle. 95

2. A trolley-pole adapted to be supported

at one end and carrying a trolley-wheel at the other, the pole being bent intermediate its ends so that a portion of the pole may be below the top of the trolley-wheel and the supporting end.

3. A trolley-pole adapted to be supported at one end and carrying a trolley-wheel at the other, the pole being shaped intermediate its ends so that a portion of the pole may

be below the top of the trolley-wheel and the supporting end.

In witness whereof we have hereunto set our hands this 15th day of September, 1902.

CHARLES A. BRAY.
FLORIEN C. FRY.
